[57] CLAIM

The ornamental design for video disc player, as shown
and described.

DESCRIPTION

FIG. 1 is a front, top and left side perspective view of a
video disc player showing our new design;

FIG. 2 is a rear, bottom and right side perspective view
thereof;

FIG. 3 is a top plan view thereof;

FIG. 4 is a right side elevational view thereof;

FIG. 5 is a left side elevational view thereof; and

FIG. 6 is a front elevational view thereof with a front
cover pivoted to open position.
